DES. 2170

Jacob Steffe of Philadelphia Pa.

Assign to

Cox, Whitteman & Cox of same place
Letters Patent No. 2170 Dated Sept 12, 1865

Design for a Stove.

The schedule referred to in these Letters Patent and making part of the same.

To all whom it may concern:

Be it known that I, Jacob Steffe, of the City of Philadelphia, in the State of Pennsylvania, have invented or produced a new and original Design for a Stove, which, for ready distinction, from other stoves, I call the "Picket," and of which the following is a full, clear, and exact description, reference being had to the accompanying perspective drawing or figure, making part of this specification.

The said design may, for convenience of reference, be divided into three general parts, and of which A is the base; B the cap; and C the intermediate portion or body.

The base A is formed, and ornamented with the raised beads or moldings a-a, and the raised figures a²-a² as represented in the drawing.

The body C is nearly in the form of the first arm of an elliptic spindle placed vertically on the base A, has the longitudinal corrugations C-C', and is surmounted at its middle by the horizontal circular plane or flange c, ornamented as shown.

The cap B is formed so as to surmount and project over the body C, as shown in the drawing, and is also ornamented with an edge molding b' having raised ornamental figures thereon as shown.

Having thus described my invention or production,
What I claim as new and desire to secure by letters
patent is,

A design, for a stave, consisting of the combi-
nation and arrangement of the forms and figures of the
base A, cap B, and body C, as shown.
